SAUCER

William E. Jones, 3951 Shannon Drive, Fort Worth, Tex.

Filed Sept. 24, 1959, Ser. No. 57,671

Term of patent 14 years

(Cl. D44—9)

FIG. 1.

FIG. 2.

FIG. 3.

FIG. 4.

FIGURE 1 is a top plan view of a saucer showing my new design.

FIGURE 2 is a side elevation view.

FIGURE 3 is a bottom plan view, and

FIGURE 4 is a broken transverse sectional view.

The characteristic feature of my design resides in the three part division and the narrow ridges at the outer edges thereof, and the rounded bottom flared divided grooves extending outwardly of said ridges relative to the center of the design.

I claim:

The ornamental design for a saucer, substantially as shown and described.
